UNITED STATES PATENT OFFICE

JACQUE C. MORRELL, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS FOR TREATING PETROLEUM OILS

No Drawing. Application filed April 27, 1923, Serial No. 635,123. Renewed March 15, 1928.

This invention relates to improvements in a process for treating petroleum oil and refers more particularly to the increase of low boiling point hydrocarbons in cracked distillates.

5 The invention further has to do with a process in which the hydrocarbon oil during treatment is subjected to a refining action simultaneously with the conversion of the oils into relatively low boiling point products.

10 The process is carried out by treating the oil in any suitable type of cracking unit, either a shell or tube still provided with an expansion zone in which the heated oil is permitted to cool and vaporize. During 15 treatment the oil is subjected to a conversion temperature and a vapor pressure regulated to maintain upon the oil a pressure relative to the temperature in order to effect the most desirable cracking conditions. These conditions will vary within a considerable range, 20 as the different oils require different conditions of temperature and pressure to produce the most complete conversion.

25 The invention resides in having present during the conversion of the oil permanganates, particularly the permanganates of potassium and sodium. These re-agents are 30 preferably introduced into the still and the distillation carried on while they are in intimate contact with the oil undergoing treatment. It has been found, particularly with the conversion of such oils as kerosene and cracked distillate when distilled in the presence of such re-agents, that there is produced 35 an increased amount of low boiling point fractions. This increase is somewhat augmented by the introduction of an oxidizing gas such as air, oxygen, or ozone. The manganese compound remaining in the still may 40 be recovered by suitable methods and the substance again re-used with further distillations.

45 The oxidizing reaction should be carried out to the extent of refining the oil particularly to remove objectionable sulphur compounds and improve the product by the presence of oxygen-containing compounds. Oxidation to the extent of approximately 5% 50 will serve for refining purposes, whereas up-

ward of 5%, say up to 25%, may be desirable for producing oxygen derivatives.

In this connection it has been found that the use of such re-agent to the amount of ten per cent will increase the low boiling point hydrocarbons produced from five to ten 55 per cent. These figures, however, are relative and may be varied without departing from the scope of the invention. In certain cases it may be desirable to increase or decrease this percentage of permanganate present during the treatment of the oil to produce the best results. The substance acts partially as a catalyst and seems also to have a particularly desirable chemical action. Although there is an increased amount of low boiling point products, there is also a decidedly advantageous effect of the presence of this re-agent in that the resultant products 60 are of a more refined nature, being of a relatively sweet odor and substantially devoid of objectionable coloring matter.

65 Reference is made to the fact that this conversion or treatment of the oil takes place under pressure. It has been found under 70 certain conditions and in connection with certain oils that the treatment is as satisfactory under atmospheric pressure as when a super-atmospheric pressure is imposed. The preferable temperature range, however, has been 75 found to be from approximately 700° F. to 925° F. while preferential pressures range from 50 pounds per square inch to 300 pounds per square inch.

I claim as my invention:

80 1. A process of converting substantial percentages of relatively high boiling point oils into lower boiling point oils and in simultaneously refining said lower boiling point oils, consisting in heating and vaporizing oil at a conversion temperature in the presence of permanganates not in excess of 10% by weight of the oil treated, of a metallic substance, in introducing during the reaction period an oxidizing gas, in condensing and collecting the evolved vapors and in maintaining a regulated vapor pressure upon the oil undergoing treatment.

85 2. A process for producing low boiling oil from higher boiling oil and for simultaneous 90

ly refining the former which comprises cracking the higher boiling oil by subjection to cracking conditions of temperature and pressure in the presence of a metallic permanganate not in excess of 10% by weight of the oil treated and recovering the low boiling hydrocarbons thereby produced.

3. A process for producing low boiling oil from higher boiling oil and for simultaneously refining the former which comprises distilling the higher boiling oil in the presence of a metallic permanganate not in excess of 10% by weight of the oil treated at a temperature and under a superatmospheric pressure adequate to effect substantial cracking and condensing the resultant vapors.

4. A process for producing low boiling oil from higher boiling oil and for simultaneously refining the former which comprises cracking the higher boiling oil by subjection to cracking conditions of temperature and pressure in the presence of a metallic permanganate not in excess of 10% by weight of the oil treated and an oxidizing gas, and recovering the low boiling hydrocarbons thereby produced.

5. A process for producing low boiling oil from higher boiling oil and for simultaneously refining the former which comprises distilling the higher boiling oil in the presence of a metallic permanganate not in excess of 10% by weight of the oil treated and an oxidizing gas at a temperature and under a superatmospheric pressure adequate to effect substantial cracking and condensing the resultant vapors.

JACQUE C. MORRELL.
